CLAIM

The ornamental design for a carafe, as shown and described.

DESCRIPTION

FIG. 1 is a perspective view of a carafe showing my new design;

FIG. 2 is an exploded perspective view thereof;

FIG. 3 is a top plan view thereof, and,

FIG. 4 is a sectional view taken along line 4-4 of FIG. 3. The broken lines are shown for illustrative purposes only and form no part of the claimed design.
